UNITED STATES PATENT OFFICE.

EDWIN NORTON, OF MAYWOOD, ILLINOIS, ASSIGNOR TO THE NORTON BROS., OF CHICAGO, ILLINOIS.

AUTOMATIC SHEET-METAL-ROLLING MILL.

SPECIFICATION forming part of Letters Patent No. 600,165, dated March 8, 1898.

Application filed July 22, 1897. Serial No. 645,490. (No model.)

To all whom it may concern:

Be it known that I, EDWIN NORTON, a citizen of the United States, residing in Maywood, in the county of Cook and State of Illinois, have invented a new and useful Improvement in Automatic Sheet-Metal-Rolling Mills, of which the following is a specification.

My invention relates to sheet-metal-rolling mills.

- 10 In sheet-metal-rolling mills heretofore in use in this and other countries for reducing bars of iron or steel into thin sheets—such as are rolled in packs to comparatively thin gages and used for tin-plate, black plate, and sheet-
15 iron—it has always been customary to employ a number of skilled operators commonly known as the “roller-man,” who has general charge of the mill and who feeds the heated bars or packs to the rolls; the “catcher,” who
20 catches the bars or packs as they emerge from the rolls with iron tongs and returns them over the top of the rolls to the roller-man ready for the next pass, and the “screw-man,” who operates or turns the feed or adjusting
25 screws, by which the rolls are set closer together after each pass, the operation being repeated again and again until the packs are the desired thickness. From time to time the bars or packs are returned to the furnace and
30 reheated.

The object of my invention is to provide an automatic sheet-metal-rolling mill for performing the operations heretofore done by hand by the several skilled workmen above mentioned.

- 35 My invention consists in an automatic sheet-metal-rolling mill comprising rolls to reduce the metal to the desired thickness; feed-tables to feed the series of bars, sheets, or packs to
40 the rolls and to receive the same from the rolls; feed or adjusting screws to set the rolls closer and closer together as the rolling proceeds, and automatic mechanism for turning the feed or adjusting screws down to effect
45 the successive reductions by a predetermined number of passes of the metal between the rolls and then automatically running the feed-screws back to position for repeating the operation on the next series of bars, sheets, or
50 packs, whereby the mill is caused to make a predetermined number of passes of the metal

between the rolls and each with a predetermined amount or degree of reduction with comparative rapidity and before the metal loses its heat and then automatically return 55 to place for repeating the operation, thus effecting a great saving of skilled and high-priced labor and at the same time producing a much greater aggregate reduction of the metal at each heat, and also entirely obviating 60 all danger of straining the mill or breaking the rolls, as heretofore has frequently happened owing to the carelessness or mis-judgment of the operatives in setting the rolls closer together for the next pass. 65

My invention further consists, in connection with the rolls adapted to pass the bars or sheets between them successively in opposite directions and feed screws or devices for setting the rolls closer together after each successive pass, of mechanism for automatically turning or adjusting the feed screws or devices after each successive pass and mechanism for automatically changing or regulating the extent to which the feed screws or devices 70 75 are turned or moved after each pass or after any given number or series of passes, so that as the metal cools a less and less reduction may be effected at each pass or at each pass of each successive series of passes. 80

It further consists in providing the feed-table with movable gages or guides which are automatically operated to square or true up and center the bars or sheets on the feed-table after each pass preparatory to their being 85 again passed between the rolls.

It further consists in the combination, with the rolls and feed-table or feed devices upon which the sheets rest, of a sheet trimming or shearing mechanism to which the sheets are 90 delivered by the feed-table of the rolling-mill.

It further consists in the combination, with the rolls and feed-table, of a pack shearing and slitting mechanism.

It also consists in the novel construction of 95 parts and devices and in the novel combinations of parts and devices herein shown and described, and specified in the claims.

The feed-screws are turned at intervals by connecting them with a power-driven pulley 100 through a suitable clutch, and they are automatically operated after each pass, at the

beginning of each reversal of the rolls, preferably by means of a cam frictionally connected to the shaft of the driven roll and which, through suitable connecting mechanism, controls the operation of the clutch through which the feed-screws are connected with their driving-pulley, although any other suitable mechanism may be employed for thus automatically operating or turning the feed-screws at each reversal of the motion of the mill. The means or mechanism which I prefer to employ for automatically changing or regulating the extent to which the feed-screws are turned, after each pass or after each successive series or number of passes, consists in a set of gears of different diameters which successively engage a set of segment-gears of different diameters and which are interposed in the connecting mechanism or gearing connecting the feed-screws with their driving-shaft, although any other suitable means or mechanism may be employed in the combination as the equivalent of the set of gears and segments of different diameters. By this means I am enabled after each pass of the bars or sheets between the rolls not only automatically to set or adjust the rolls for the next pass, but also after any pass or any given number or series of passes— as, for example, five—to automatically change or regulate the extent to which the feed-screw shall be turned at each pass or at each pass of the next succeeding series of, say, five passes, and so on, thus accommodating the action of the mill to the changed conditions of the sheets or bars due to the lapse of time and loss of temperature as the rolling proceeds.

In the drawings I have illustrated my sheet-metal-rolling mill as being arranged and adapted to turn or adjust the feed-screws an equal extent for each of a series of five passes, and then an equal but less extent for each of a succeeding series of five passes, and then an equal but still less extent for each of a final series of five passes; but it will be understood that by simply changing the intermeshing gears and segments and employing a greater or less number of gears and segments the automatic changing or regulating of the extent to which the feed-screws are turned may be made to occur with greater or less frequency or after each and every pass, if desired, or as may be required for the particular nature of the work being done by the mill. By this means I am enabled to save or entirely dispense with the skilled and high-priced labor heretofore employed for turning or adjusting the feed-screws after each pass for feeding or passing the sheets centrally and squarely to the rolls and for returning the sheets to the rolls after each pass, and at the same time I am also enabled to make the successive passes much more expeditiously, and thus effect a much greater reduction at each heat. I also entirely obviate all danger of breaking the rolls by improper

adjustment of the feed-screws, an occurrence which very frequently happens, owing to the carelessness or misjudgment of the screw-man. 70

In the drawings similar letters of reference indicate like parts throughout all the figures.

In said drawings, Figure 1 is a plan view of a sheet-metal-rolling mill embodying my invention. Fig. 2 is a front elevation looking from 75 the line 2 2 of Fig. 1 in the direction of the arrow. Fig. 3 is a side elevation. Fig. 4 is an enlarged detail plan view illustrating the mechanism which I prefer to employ for changing or regulating the extent to which 80 the feed-screws are turned at or in each successive series of passes. Fig. 5 is an enlarged partial vertical section taken on the line 5 5 of Fig. 4. Fig. 6 is a detail plan view of the mechanism for operating the movable gages 85 of the roller feed-table, and Fig. 7 a detail elevation of the same.

In the drawings, A represents the frame of the machine.

B B' are the rolls, the lower one B being 90 the driven roll. C is the feed-table upon which the bars or sheets rest and by which they are fed or passed back and forth between the rolls successively in opposite directions.

D D' are the feed-screws turning in the housings D' of the frame, by which the rolls are set closer and closer together after each successive pass. The lower ends of these feed-screws press against the bearings B² of 100 the shaft B³ of the upper roll.

The feed-screws D D' are turned at intervals by power communicated to them from the feed-screw-driving pulley F³ through suitable connecting mechanism or gearing, including a clutch F' F², by which the shaft F is connected at intervals to the driving-pulley F³. 105

The means or mechanism employed to operate the clutch F' F² after each successive 110 pass, at the reversal of the motion of the mill, consists, preferably, of an oscillating cam G, secured frictionally to the shaft B³ of the lower roll B, and which is adapted to oscillate slightly to one side or the other until it 115 engages one or the other of the stops G' G', attached to the frame. The frictional connection between the cam G and shaft B³ permits the roll to continue its rotation after the cam engages the stop, while at the same 120 time causing the clutch F' F² to be operated and the turning of the feed-screws to set the rolls for the next pass to be made at the beginning of the reversal of the motion of the mill and before the feed-table C enters the 125 bars or sheets between the rolls.

Any suitable connecting mechanism may be employed for communicating motion from the cam G to the movable member of the clutch F' F²; but I prefer to employ for this purpose a reciprocating slide g, having a pin or roller g', engaging the cam, and which is provided at its upper end with a pawl or dog g², which is adapted to engage a collar or pro-

jection g^3 on the clutch-operating rod g^4 . A spring g^5 holds the pawl normally in position to engage said collar. A stationary cam g^6 , engaging the free end of the pawl or dog g^2 , causes it to disengage said collar on the clutch-rod, after having first operated the clutch-rod, so that the spring g^7 on the clutch-rod may return it to position to again disengage the clutch after the shaft F has made one revolution. The shaft F is provided with a gear F^4 , engaging a gear F^5 on a shaft F^6 , said gears being preferably so related to each other that the shaft F^6 makes, for example, one revolution to every five revolutions of the shaft F.

15 The means or mechanism which I prefer to employ for automatically changing the extent to which the feed-screws are turned at each pass or after any given number or series of passes—say, for example, five—consists in inserting in the connecting mechanism or gearing by which motion is communicated from the shaft F to the feed-screw shaft a set of gears of different diameters H H' H², preferably three in number, and a corresponding set of segment-gears $h h' h^2$ of different arc lengths and arranged one after another, or each at the point where its predecessor terminates, as will be readily understood from Figs. 4, 5, and 2.

30 If it is desired to change or regulate the extent to which the feed-screws are turned more or less frequently than illustrated in the drawings, all that is required is simply to substitute for the gears F^4 and F^5 other similar gears having a different relation to each other and for the set of gears and segments H h H' h' H² h² other sets or a greater or less number of similar gears and segments, and thus any desired frequency of change or regulation of the extent to which the feed-screws are turned may be produced, or after each and every pass, if desired.

35 The feed-screws D D are geared together, so as both to rotate in the same direction by gears D² D² through an intermediate gear D³. The gears D², instead of being fixed directly to the shafts of the feed-screws D D, are connected thereto through the medium of worm-gears D⁴ D⁴, which fit on the squared ends 40 of the shafts of the screws D D, and which worm-gears engage worms D⁶ D⁶, journaled in brackets on the gears D², so that by turning the worms D⁶ by hand the screws D may each be independently turned or adjusted 45 in respect to each other as may be required from time to time to compensate for wear or to bring the rolls B B' truly parallel to each other. The set of segment-gears h h' h², which successively mesh with the set of 50 gears H H' H², are secured to or formed integral with the gear D² on one of the feed-screws. The gear D² on the other feed-screw is provided with a bevel-gear D⁷, which meshes 55 with a bevel-gear K on the shaft K', which is connected by a clutch K² K³ with the driving-pulley K⁴, by which the feed-screws D are

turned back or unscrewed after the rolling of the bars or packs on the feed-table C is finally finished or completed for the heat. This clutch K² K³ is automatically operated after 70 the rolling is thus completed by a cam K⁵ on one of the gears D² engaging a lever K⁶, from which, through suitable connections K⁷ K⁸ K⁹, motion is communicated to the movable member of said clutch. 75

The feed-table C may be of any suitable kind or construction adapted to feed or pass the sheets in opposite directions after each successive pass. It is preferably what is commonly known as a "roller" feed-table 80 and comprises a series of rolls c, having beveled gears c', engaging bevel-gears c² on the shafts c³ c³. Motion is communicated to the shafts c³ in opposite directions as the motion of the mill is reversed, preferably by providing the shaft of the driven roll B with the bevel-gear b, engaging a bevel-gear b' on the shaft b², which has a second gear b³, engaging a gear b⁴ on the shaft b⁵, from which motion is communicated to the shafts c³ by the pulleys b⁶ b⁷ and connecting-belts. 85 90

The feed-table C is furnished with movable gages or guides C' C' at its opposite edges, which are automatically operated to approach each other after each pass of the bars or sheets between the rolls, and thus by grasping the bars or sheets at their side edges to automatically true or square up and center all the bars or sheets on the feed-table preparatory to their being again passed between the rolls, 95 so that they will all enter the rolls smoothly and centrally with the rolls. After the bars and sheets are thus automatically adjusted properly in position on the roller feed-table the gages or guides again open or separate, 105 and thus permit the bars or sheets to be fed forward by the roller feed-table into the rolls without friction-contact with the gages. The gages or guides C' C' may thus be automatically operated after each pass by any suitable means or mechanism, but preferably by a cam or arm C², frictionally secured to the shaft B³ of the driven roll B, similarly to the friction-cam G, and which is adapted to vibrate from one of the stops C⁴ C⁴ to the other 115 at each reversal of the rolls and which is connected to the slides C⁵ C⁵, carrying the opening and closing gages C' C', preferably by means of a link C⁶, pivoted to the friction cam or arm C² and to a lever or arm C⁷, which is connected by a link C⁸ with a rack C⁹, that meshes with a gear C¹⁰ on a rack-shaft C¹¹, that is provided with a pair of lever-arms C¹² C¹³, connected by links C¹⁴ C¹⁴ and intermediate levers C¹⁵ with the gage-carrying slides 125 C⁵ C⁵, so that at each movement of the friction cam or arm C² the two gages C' C' are first made to momentarily close or approach each other to center and square the bars or sheets on the feed-table, and then at once to 130 open or separate to permit the bars or sheets to be fed forward into the bite of the rolls.

without again touching the gages, which might otherwise tend to disarrange the bars or sheets on the table before entering the rolls.

M represents the mechanism for squaring, 5 trimming, or shearing the end edges of the sheets after the rolling has been completed. It may be of any suitable construction known to those skilled in the art and needs no special or detailed description. The sheets are delivered 10 from the roller feed-table C of the rolling-mill onto a feed-table M', from which the sheets to be trimmed are fed or passed between the rotary cutters M² of the sheet-trimming mechanism. Feed-rollers M³ serve 15 to feed the sheets onto this feed-table M'. The sheet-trimming mechanism which I prefer to employ and which I have indicated in the drawings is that shown and described in Letters Patent No. 560,065, granted May 12, 20 1896, to John G. Hodgson.

N represents a mechanism for trimming and subdividing or slitting packs of metal sheets as they are delivered from the feed-table of the rolling-mill. This trimming and slitting 25 mechanism may be of any suitable kind known to those skilled in the art and therefore needs no detailed description. The mechanism for this purpose which I prefer to employ and which I have therefore illustrated in a general 30 way in the drawings is that shown and described in Letters Patent No. 560,064, granted May 12, 1896, to John G. Hodgson.

The packs of sheets after being rolled are delivered by the roller feed-table C of the 35 rolling-mill directly onto the feed-table N' and between the feed-rolls N² of the trimming and slitting or subdividing mechanism, and thence between the rotary trimming-cutters N³, thence between the feed-rollers N⁴ to the 40 roller feed-table N⁵ of the slitting or subdividing mechanism, and thence passed transversely between the feed-rollers N⁶ to the slitting or subdividing rotary cutters N⁷, and thence out of the machine between the delivery-rolls N⁸.

In operation the motion of the driven roll B may be reversed by any suitable mechanism after each pass; but this is preferably done by simply reversing the engine by which 50 the mill is driven.

To enable the mill to be run any desired number of passes without feeding, setting, or adjusting the rolls closer together, as is sometimes desired, I provide the mill with means 55 for fixing the cam G stationary. This means may preferably consist of a pin g⁸, inserted through the cam and entering a hole g⁹ in the frame.

To provide the mill with means for readily 60 setting or adjusting the feed-screws to any required thickness of metal or to any required distance of the rolls B B' apart when the feed-screw-driving gears are turned completely around or down, I provide two gage plates or 65 disks to fit between the end of the feed-screw and the bearing of the upper roll, one of which is less in thickness than the other by the thick-

ness of metal to which the bars, sheets, or packs are designed to be finished, so that in setting or adjusting the mill the thicker gage-plate P may be inserted and the rolls then set down directly together, the screws being at this time turned down ready for re-turning, after which the thicker gage-plate is removed and the thinner one P' inserted in its place. 70 This makes an easy and expeditious means for setting or adjusting the mill to any required thickness designed to be rolled. These gage-plates, in connection with the feed-screws, also serve as a ready means for readjusting or resetting the mill to compensate for wear. 80

The same mill may be employed for rolling bars or plates, as a roughing-mill, or for rolling packs of thin sheets, and for this reason 85 I combine with the same mill both a trimming and shearing mechanism for trimming or squaring the ends of the single sheets rolled from the bars, and also a pack trimming and subdividing mechanism for the finished packs. 90 After the rolling has been completed to deliver the bars, plates, sheets, or packs to either of the cutting mechanisms the mill is simply continuously driven in the same direction in which it was rotated for the last 95 pass until all the several packs, plates, or sheets on the roller feed-table C are delivered onto the feed-table of the cutting mechanism.

I claim—

1. An automatic rolling-mill for reducing 100 bars to thin sheets, or packs of sheets to thinner gages, consisting of rolls to reduce the metal to the desired thickness, feed-tables to feed the metal to the rolls and to receive it from the rolls, gages to center the metal on the feed-tables, feed-screws for adjusting the rolls, and automatic means for turning the feed-screws whereby the mill is caused to make a predetermined number of reductions 105 of the metal and then return to place for commencing another similar series of reductions without the aid of skilled workmen, substantially as specified.

2. In an automatic rolling-mill, the combination with rolls to reduce the metal, of a feed-table to feed the metal to the rolls and receive it from the rolls, parallel opening and closing guides one on each side of the feed-table to center the metal sheets or bars on the table, feed-screws for setting the rolls closer together 120 after each successive pass, automatic mechanism for turning the feed-screws after each successive pass, and means for automatically moving the guides after each pass, substantially as specified.

3. In an automatic rolling-mill, the combination with rolls to reduce the metal of a feed-table to feed the metal to the rolls and receive it from the rolls, parallel opening and closing guides one on each side of the feed-table to center the metal sheets or bars on the table, feed-screws for setting the rolls closer together after each successive pass, automatic mechanism for turning the feed-screws after each 125 130

successive pass, mechanism for automatically changing or regulating the extent to which the feed-screws are turned after any given pass or series of passes for the next successive 5 pass or series of passes, and means for automatically moving the guides after each pass, substantially as specified.

4. The combination with the feed-table and rolls, of the feed-screws for setting the rolls closer together after each successive pass, and mechanism for automatically turning the feed-screws after each successive pass consisting in a cam frictionally connected to the shaft of the roll, and connections between 15 said cams and feed-screws, substantially as specified.

5. The combination with the feed-table and rolls, of the feed-screws for setting the rolls closer together after each successive pass, 20 mechanism for automatically turning the feed-screws after each successive pass, and mechanism for automatically changing or regulating the extent to which the feed-screws are turned after any given pass or series of 25 passes for the next succeeding pass or series of passes, consisting in a set of gears of different diameters, and a corresponding set of segment-gears of different diameters arranged one after another and interposed in the connecting 30 mechanism through which motion is communicated to the feed-screws, substantially as specified.

6. The combination with the feed-table and rolls, of the feed-screws for setting the rolls closer together after each successive pass, mechanism for automatically turning the feed-screws after each successive pass, consisting in a cam frictionally connected to the shaft of the roll, and mechanism for automatically changing or regulating the extent to which the feed-screws are turned after any given pass or series of passes for the next succeeding pass or series of passes consisting in a set of gears of different diameters, and 45 a corresponding set of segment-gears of different diameters arranged one after another and interposed in the connecting mechanism through which motion is communicated to the feed-screws, substantially as specified.

50 7. The combination with the feed-table and rolls, of the feed-screws for setting the rolls closer together after each successive pass, mechanism for automatically turning the feed-screws after each successive pass, and mechanism for automatically returning or 55 running back the feed-screws, substantially as specified.

8. The combination with the feed-table and rolls, of the feed-screws for setting the rolls closer together after each successive pass, mechanism for automatically turning the feed-screws after each successive pass, mechanism for automatically changing or regulating the extent to which the feed-screws are 60 turned after any given pass or series of passes for the next succeeding pass or series of passes, and mechanism for automatically re-

turning or running back the feed-screws, substantially as specified.

9. In a rolling-mill, the combination with 70 the rolls adapted to be driven in opposite directions, of the feed-screws for setting the rolls closer together after each pass, a feed-screw-driving shaft, clutch and connecting mechanism for turning the feed-screws, and 75 a cam and connecting mechanism for operating the clutch at each reversal of the motion of the rolls, substantially as specified.

10. In a rolling-mill, the combination of 80 the rolls adapted to be driven in opposite directions, of the feed-screws for setting the rolls closer together after each pass, a feed-screw-driving shaft, clutch and connecting mechanism for turning the feed-screws, a cam and 85 connecting mechanism for operating the clutch at each reversal of the motion of the rolls, and mechanism for automatically changing or regulating the extent to which the feed-screws are turned after any given pass or series of 90 passes for the next succeeding pass or series of passes, substantially as specified.

11. In a rolling-mill, the combination with 95 the rolls adapted to be driven in opposite directions, of the feed-screws for setting the rolls closer together after each pass, a feed-screw-driving shaft, clutch and connecting mechanism for turning the feed-screws, a cam and connecting mechanism for operating the clutch at each reversal of the motion of the rolls, and a set of gears of different 100 diameters, and a corresponding set of segment-gears of different diameters interposed in the connecting mechanism through which motion is communicated to the feed-screws, substantially as specified.

105 12. In a rolling-mill, the combination with the rolls adapted to be driven in opposite directions, of the feed-screws for setting the rolls closer together after each pass, a feed-screw-driving shaft, clutch and connecting 110 mechanism for turning the feed-screws, a cam and connecting mechanism for operating the clutch at each reversal of the motion of the rolls, a set of gears of different diameters, a corresponding set of segment-gears of different 115 diameters interposed in the connecting mechanism through which motion is communicated to the feed-screws, and mechanism for running back or unscrewing the feed-screws after the rolling is completed, substantially as specified.

120 13. In a rolling-mill, the combination with the rolls adapted to be driven in opposite directions, of the feed-screws for setting the rolls closer together after each pass, a feed-screw-driving shaft, clutch and connecting 125 mechanism for turning the feed-screws, a cam and connecting mechanism for operating the clutch at each reversal of the motion of the rolls, a set of gears of different diameters, a corresponding set of segment-gears of different 130 diameters interposed in the connecting mechanism through which motion is communicated to the feed-screws, mechanism for

running back or unscrewing the feed-screws after the rolling is completed, and a cam for setting said unscrewing mechanism in operation, substantially as specified.

5 14. In a sheet-metal-rolling mill, the combination with the rolls and feed-table, of a rotary-cutter sheet trimming or cutting mechanism having cutters for each end of the sheet to which the rolled sheets are delivered directly by the feed-table of the mill, said feed-table having devices for feeding or conveying the sheets both to the rolls and to said trimming or cutting mechanism, and movable gages on opposite sides of said feed-table to center the sheets on the table before entering the rolls or entering the trimming or cutting mechanism, substantially as specified.

15 15. In a sheet-metal-rolling mill, the combination with the rolls and feed-table, of a rotary-cutter sheet-metal trimming and slitting or subdividing mechanism to which the sheets are delivered directly by the feed-table of the mill, said feed-table having devices for feeding or conveying the sheets both to the rolls and to said trimming and slitting or subdividing mechanism and movable gages on opposite sides of said feed-table to center the sheets on the table before entering the rolls or entering the trimming and slitting or subdividing mechanism, substantially as specified.

20 16. In a sheet-metal-rolling mill, the combination with the rolls and feed-table, of a sheet trimming or cutting mechanism to which the rolled sheets are delivered directly from the feed-table of the mill, and a sheet-metal trimming and subdividing mechanism, said feed-table having devices for feeding or conveying the sheets to said rolls, to said trimming or cutting mechanism and to said trimming and subdividing mechanism, and movable gages on the opposite sides of said feed-table to center the sheets on the table before entering the rolls, the trimming or cutting mechanism, or the trimming and subdividing mechanism, substantially as specified.

25 17. The combination with the feed-table and rolls, of the feed-screws for setting the rolls closer together after each successive pass, automatic mechanism for turning the feed-screws after each successive pass, parallel movable guides for automatically truing and centering the bars or sheets on the feed-table after each successive pass, and means for automatically moving the guides after each pass, substantially as specified.

30 18. The combination with the feed-table and rolls, of the feed-screws for setting the rolls closer together after each successive pass, automatic mechanism for turning the feed-screws after each successive pass, parallel movable gages for automatically truing and centering the bars or sheets on the feed-table after each successive pass, and automatic mechanism for opening and closing the gages after each pass, substantially as specified.

35 19. The combination with the feed-table and rolls, of the feed-screws for setting the rolls closer together after each successive pass, mechanism for automatically turning the feed-screws after each successive pass, mechanism for automatically changing or regulating the extent to which the feed-screws are turned after any given pass or series of passes for the next succeeding pass or series of passes, parallel movable guides for automatically truing and centering the bars or sheets on the feed-table after each successive pass, and means for automatically moving the guides after each pass, substantially as specified.

40 20. The combination with the feed-table and rolls, of the feed-screws for setting the rolls closer together after each successive pass, mechanism for automatically turning the feed-screws after each successive pass, and mechanism for automatically changing or regulating the extent to which the feed-screws are turned after any given pass or series of passes for the next succeeding pass or series of passes, consisting in a set of gears of different diameters, and a corresponding set of segment-gears of different diameters arranged one after another and interposed in the connecting mechanism through which motion is communicated to the feed-screws, and movable gages for automatically truing and centering the bars or sheets on the feed-table after each successive pass, substantially as specified.

45 21. The combination with the feed-table and rolls, of the feed-screws for setting the rolls closer together after each successive pass, automatic mechanism for turning the feed-screws after each successive pass, and a rotary sheet-trimming mechanism to which the rolled sheets are delivered directly from the feed-table of the mill, said feed-table having devices for feeding or conveying the sheets both to the rolls and to said trimming mechanism, and movable gages on opposite sides of said feed-table to center the sheets on the table before entering the rolls or entering the trimming mechanism, substantially as specified.

50 22. The combination with the feed-table and rolls, of the feed-screws for setting the rolls closer together after each successive pass, automatic mechanism for turning the feed-screws after each successive pass, and a rotary sheet trimming and slitting or subdividing mechanism to which the sheets are delivered directly by the feed-table of the mill, said feed-table having devices for feeding or conveying the sheets both to the rolls and to said trimming and slitting mechanism and movable gages on opposite sides of said table to center the sheets on the table before entering the rolls or entering the trimming and slitting mechanism, substantially as specified.

55 23. The combination with the feed-table and rolls, of the feed-screws for setting the rolls closer together after each successive

pass, mechanism for automatically turning the feed-screws after each successive pass, mechanism for automatically changing or regulating the extent to which the feed-screws are turned after any given pass or series of passes for the next succeeding pass or series of passes, and a rotary sheet-trimming mechanism to which rolled sheets are delivered directly from the feed-table of the mill, said feed-table having devices for feeding or conveying the sheets both to the rolls and to said trimming mechanism, and movable gages on opposite sides of said feed-table to center the sheets on the table before entering the rolls or entering the trimming mechanism, substantially as specified.

24. The combination with the feed-table and rolls, of the feed-screws for setting the rolls closer together after each successive pass, mechanism for automatically turning the feed-screws after each successive pass,

mechanism for automatically changing or regulating the extent to which the feed-screws are turned after any given pass or series of passes for the next succeeding pass or series of passes, and a rotary sheet-trimming or subdividing mechanism to which the sheets are delivered directly by the feed-table of the mill, said feed-table having devices for feeding or conveying the sheets to said rolls, to said trimming or cutting mechanism and to said trimming and subdividing mechanism, and movable gages on the opposite sides of said feed-table to center the sheets on the table before entering the rolls, the trimming or cutting mechanism, or the trimming and subdividing mechanism, substantially as specified.

EDWIN NORTON.
